UNITED STATES PATENT OFFICE

ISAAC ROET, OF AMSTERDAM, NETHERLANDS

CIGARETTE-MAKING MACHINE

Application filed March 18, 1927, Serial No. 176,531, and in the Netherlands March 20, 1926.

This invention relates to apparatus for the simultaneous production of a number of cigarettes. According to the invention a strip of cigarette paper is unwound from a bobbin by means of a transporter and brought into a position opposite to a number of members in which the paper, after it has been divided by simultaneously moved knives into a number of parts corresponding to the number of cylindrical cases can be slipped simultaneously into the said cases for the preparation of the cigarettes. To each of these cases there belongs a so-called ram, which is so constructed as to be movable up and down and also rotatable and which rolls up the paper in the case into a tube, tamps the tobacco one or more times, and expels the cigarette from the case.

The feeding of the paper into the desired position over the cylindrical cases is obtained by means of periodically moved endless steel bands which are provided with preferably resilient clamps, the mutual distances of which correspond to the length of the paper necessary for the number of cigarettes to be simultaneously prepared, during each period of operation which grip the paper coming from the bobbin or storage roll and guide it to the cigarette members.

According to the invention the group of cylindrical cases consists of a row of cylinders, each provided with a gap which is provided along a generating line and into which, for all the cylinders at the same time, a piece of the cut-up strip of cigarette paper is pushed.

This pushing in of the paper is effected by means of pushers which are moved simultaneously with the cutting knives and which push the paper immediately after it is cut off along the generating line into the cylindrical cases.

Above each case is arranged a movable filling hopper, which is provided with a prolongation piece which is located in the centre line of the case and around which one of the outer ends of the paper sleeve is coiled, the paper being held fast if necessary in case of need by a nipping device round the extension piece.

For the rolling of the paper sleeve the ram is provided with one or more expandible parts,

which press the inserted paper against the inner wall of the case and carry it round during the rotation of the ram.

If the apparatus is being utilized for the preparation of cigarettes which are to be folded in at one or both ends, the cylindrical cases are provided according to the invention at one or both ends with folding bodies, the movements of which proceed simultaneously for all the members.

The movements of the folding apparatus may according to the invention be effected in such a way that at the end of the member at which the introduction of the ram does not take place, the paper tube already formed is folded before the tobacco is guided into the cylindrical cases.

For the feeding of the tobacco into the cylindrical cases there is fitted a distributing roll, which is provided on its periphery with a number of grooves for each cylindrical case corresponding to the number of stadia on which the fillings of the paper tube is effected. The grooves move during the rotation of the roller in their highest position past apertures in the tobacco storage hopper and thereupon discharge their contents in the lowest position into the hoppers that feed the paper tubes.

The invention will now be more fully described in reference to the constructional example illustrated in the accompanying drawings. Although in these drawings a modified construction is indicated only in the case of a single element it is clear that many of the parts can be constructed in some other way without abandoning the basic idea of the invention.

Figure 1 shows a front elevation partly in section, and

Figure 2 a plan of the machine.

Figure 3 is a plan of the cylindrical cases with accessories.

Figure 4 is a side elevation of the machine.

Figure 5 shows a plan, and

Figure 6 a front elevation of the transporter.

Figure 7 shows the functioning of the shears and the pushers.

Figure 8 illustrates a pair of shears.

Figure 9 illustrates the movements of the rams, and

Figure 10 the supplying of the tobacco.

Figure 11 illustrates the folding in of the sleeves, and Figure 12 the movements of the hoppers, folding arms and nippers.

Figure 13 illustrates the nippers.

Figure 14 shows how the movements of the halves of the folding arms are obtained.

10 Figure 15 shows one kind of ram.

Figure 16 shows the fastening of the rams.

Figure 17 is a plan, and

Figure 18 a rear elevation of one form of the cylinders.

15 Figure 19 illustrates the cams on the large cam disc, and

Figure 20 the fastening of the cams.

20 Figures 21, 22 and 23 show the tobacco roller with adjustable capacity and accessories.

25 The machine illustrated in the drawings serves for the continuous preparation of twenty cigarettes at a time. The paper is guided along the cylinders, whereupon it is cut up by the shears into a number of pieces equal to the number of cigarettes to be prepared.

30 After the pushers have then pushed the paper through tangential gaps into the cylinders, the rams rotate the paper into tubes. According to this constructional example the tubes are then folded in at the lower end. Then commences the filling of the tubes in one or more operations, and the tamping of the tobacco, whereupon the tubes are folded in at the top by means of folding arms, and the cigarettes are pushed out of the cylinders by the rams.

35 The motor (Figure 1), by means of belt pulleys 2, 3, 4 and 5 drives a shaft 6. From this main shaft 6, all the movements of the machine parts are obtained.

The paper supply (Figures 1, 2, 3, 5 and 6)

40 By means of bevel wheels 7 and 8 is driven a shaft 9, which transmits its motion by means of belt pulleys 10 and 11 and bevel wheels 12 and 13 to the roller 14 of a paper-transporter.

45 It is clear that the paper is to be supplied only during a part of the period of production. The pulley 10 is therefore provided on part of its periphery with a pad, which, during part of the revolution of the shaft 9, by greater tension of the belt, effects the transmission to the pulley 11, while during the remainder of the time the belt merely hangs loosely against the pulley 10 and no transmission takes place.

50 On the rollers 14 and 15 there run two endless steel bands 20. Over a pair of rollers 16, 17, there likewise run two endless steel bands 21. The paper, which is supplied from a bobbin 18 over an oblique guide 19, is carried along by resilient clamping between clamps

22 secured between the bands 20 and bars 23 fitted between the bands 21 and arranged in sets as shown. Obviously the lengths of the bands 20 and 21 are to be multiples of the distance between successive clamps 22 and between successive pairs of bars 23.

70 The clamps 22 and the bars 23 are made of india-rubber or other preferably resilient material.

A device not shown provides for the automatic stoppage of the machine in the event of the paper breaking or of the paper on the bobbin being consumed.

The cutting of the paper to size (Figures 1, 2, 3, 7 and 8)

75 A chain pulley 25, secured to the shaft 9, by means of a chain pulley 26, drives a shaft 27. Cam discs 28 arranged on the latter move a rod 30 to and fro by means of levers 29.

To this rod 30 lying in and guided by sleeves in the frame are secured readily removable arms 31, which move shear blades 32. Between these blades 32 and shear blades 33 the paper is cut off. Like the movable shear blades 32, the fixed shear blade may be secured in a simple manner to the corresponding cylinder 41, so that the shears can easily be removed as a whole.

80 It may be noted that the lower bands 20 and 21 normally occupy the space below the shear blades (Fig. 8).

The pushing of the paper into the cylinders (Figures 1, 3 and 7)

85 Cam discs 35 secured to the shaft 27 move by means of levers 36 a rod 37 by which the pushers 39 pivoted to arms 38 are moved to and fro. Accordingly during the outward stroke of the pushers 39 the cut-off paper 24 is pushed into gaps 40 in cylinders 41.

90 The paper 24 may be cut off in such a way that a small margin projects past the gap 40. The pushers 39 then make a small fold in the paper when pushing it in.

The rolling up of paper (Figures 1, 2, 3 and 9)

100 After the paper 24 has been pushed into the cylinder 41, the ram is brought into the cylinder, in a manner to be described more fully hereinafter. The ram consists of a spindle 42, with a collar 43. Upon the collar 43 rests an indiarubber ring 44, then a metal bush 45, and finally another indiarubber ring 46. After the ram has come into its low position a pressure is exerted upon the india-rubber rings, in a manner to be described later by a bush 47. In consequence of this they expand laterally and press the paper against the wall of the cylinder 41. The ram is then rotated to turn the paper into a tube, 115 and the ram is raised again.

110

120

125

130

The rotating of the rams (Figures 1, 2, 3 and 9)

A cam disc 54 secured to the shaft 27 reciprocates a rack 58 by means of a system of rods 55, 56, 57. Against this rack 58 there rest toothed wheels 59, which are secured to the rams, and by which, during the reciprocating movement of the rack 58, the rams 42 are rotated, so that the paper is rolled into tubes.

The height of the paper is greater than the height of the cylinder, so that the tube projects out of the cylinder at both ends. At the upper end it then embraces the lower end of a hopper 48.

By this means the result is obtained that the ram can easily enter the sleeve without telescoping the paper. Another object of this will be described later on. After the folding of the tube it is folded in at the bottom by folding arms (see later) before the tobacco is supplied.

The up-and-down movement of the rams (Figures 1, 4 and 9)

The up-and-down movement of the rams is effected as follows:—

By means of a cam disc 49 mounted on the shaft 6 and a roller 50 a bar 51 is moved up and down at moments to be more accurately indicated hereafter, whereby the rams 42 rotatably secured to a cross bar 52 likewise go up and down owing to rods 53.

The adjustment of the duration of the movements of the rams (Figures 1, 9, 19 and 20)

The cam disc 49 comprises engaging cams 145, which are secured to the disc with bolts 147 passing through slots 146.

The cam members 145 comprise on their peripheries portions that overlap in such a way that the roller 50, in the case of a more or less open or separated arrangement of the cam members, always rolls easily over the cams.

It is clear that by this adjustment of the cams the duration of the movements of the rams can be controlled.

The adjustment of the stroke of the rams (Figures 1 and 9)

For the purpose of adjusting the stroke of the rams for different kinds of tobacco, or when, owing to adjustment of the tobacco roller, there is a larger or smaller amount of tobacco present, the following device is fitted.

To a rock shaft 138 is secured an eccentric 139. According to the position of this eccentric 139, during the raising by the cam disc 49 of the roller 50 secured to bars 140, a link 141 will bring the bar 51, and therefore the rams 42, into a higher or lower position.

The rocking of the shaft 138 is obtained

by the action of cams or a cam disc 144 secured to the shaft 6 against a roller 143 fitted to a lever 142.

The disc 144, like the disc 49, comprises readily removable cams. According to the height chosen for these cams, the shaft 138 is rocking to a greater or less extent, and thus a larger or smaller adjustment of the stroke of the rams takes place.

The expansion of the indiarubber rings (Figures 1 and 9)

A continuous shaft 60 is supported by brackets from the cross bar 52 (see Figure 9) and therefore follows the up-and-down movement of the rams. One arm 61 of levers 61—62 loose on the shaft 60 rest by their own weight against segments 63. The condition now under consideration is when the cross bar 52, and therefore the rams 42, are in their lower positions.

Upon the shaft 27 is mounted at each end a cam disc 64. Each of these discs 64 presses against a lever 65, so that their cams, by means of systems of levers 65, 67 and link 66, cause the segments 63 arranged on a continuous shaft 68 to swing to and fro. The shape of these segments 63 is such that when the rods 65 are pushed away by the cam disc 64, and hence when the segments 63 rotate in the direction of the arrow, the arms 61 are rotated round the shaft 60 in the direction of the arrow, so that forks 62 thereon press down the bushes 47, and this movement, as has already been described, results in the expansion of the indiarubber rings.

The tobacco feed (Figures 1, 2, 4 and 10)

A tobacco-feeding roller 70 secured to a shaft 69 is driven from the shaft 27 by means of chain pulleys 71 and 72. The tobacco in a storage receptacle 73 is carried round by grooves 74 in the distributing roller 70 and supplied to the sleeves by hoppers 75 and by the hoppers 48 placed above the cylinders 41.

The adjustment of the tobacco feed (Figures 1, 2, 4, 10, 21, 22 and 23)

Figure 10 indicates a roller with grooves of constant capacity and Figure 23 shows a tobacco roller 70 which distributes the tobacco in quantities required for the filling of the paper tube in each cylindrical case. To this end the roller is provided for each cylindrical case with a number of grooves corresponding to the number of stadia in which the filling of the paper tube must be effected. The cubic measure of these grooves is adjustable according to the size of the paper tube. Therefore the roller is provided with two rings for each cylindrical case, having each over a quarter of the periphery a laterally projecting piece 149, which is reduced on the periphery in order to be covered by a

plate 150. By displacing the rings 148 with respect to each other the length of the grooves can be enlarged or reduced. The grooves for each cylindrical case are separated by a distance piece 151, secured by small screws 152 to the roller 70.

By means of the screws 153 the depth of the grooves 74 is easily adjusted.

The tamping of the tobacco and the removal 10 of the finished cigarettes (Figures 1, 4 and 9)

After complete or partial filling the tobacco is tamped by the rams 42, the rams 13 raised again, and the finished tubes folded in at both ends in a manner to be described more fully, are thrust out of the cylinders by the rams, which are again moved down. The cigarettes are then guided away through a 20 discharge channel 76.

The folding in of the paper tubes (Figures 1, 3, 11, 12, 13 and 14)

Before the tobacco is supplied the tube 23 must obviously be folded in at the bottom. This is effected by a preferably flat folding arm 77. After the complete filling the tube is also folded in at the upper end, by a preferably flat folding arm 78, whereupon, at the 30 same time it may be, two folding arms 79 and 80, preferably with a somewhat sharp edge, press the paper inwards from above and below still more, so the tube finally becomes closed.

35 As is clearly evident from Figure 11, the folding in is effected by means of the arms 77 and 78 on the descent and ascent respectively of a shaft 81, and by means of the arms 79 and 80 on the ascent of a shaft 82 and the 40 descent of a shaft 83 respectively. Fuller consideration will now be directed to the source from which these movements are obtained.

Upon the shaft 27 there is in the centre a 45 disc 84, provided with a peripheral groove 85, in which a roller 86 can slide. By this means a lever 87 receives an oscillating movement about a shaft 88. This movement is transmitted by rods 89 and 90 to shafts 93 and 94.

50 On the other ends of these shafts 93 and 94 are mounted arms 95, which, by means of rods 96, move a batten 97 up and down. The movement of this batten 97 is transmitted by the pivoted bar 98 to the shaft 81, whereby 55 ultimately the folding in of the paper is obtained by the arms 77 and 78.

Upon the shaft 27 are further mounted two 60 discs 99 with lateral cams 100, which produce the result that during the rotation of the shaft 27 shafts 101 rotate to and fro through a small angle, because the cams 100, at each revolution of the shaft 27, strike against cams 102 and 103 mounted on the shaft 101.

65 On the other ends of the shafts 101 are

mounted levers 104 which are thus set in oscillating motion by the rotation of the shaft 27. By the rotation of the shafts 101 the descent of links 105 is caused and thereby a batten 107 is pulled down, and also the simultaneous ascent of links 106 by which a batten 108 is pushed up. To these battens 107 and 108 are secured for each cylinder the shafts 83 and 82 respectively, so that during the rotation of the shafts 101 the folding arms 75 79 and 80 entirely fold in the sleeves.

The raising of the hoppers (Figures 1, 3, 9 and 12)

Before the tubes can be folded in at their 80 upper ends, the hoppers 48 must be removed. The paper has already been rolled round the hoppers at the top during the rolling up, so that, the hoppers 48 must first be removed before the folding in can be effected.

85 For this purpose there are secured to the shaft 27 two cam discs 109, which by means of levers 110 and links 111 can move a batten 112 up and down. To this batten 112 are secured the hoppers 48, which are thus raised 90 at the desired moments.

The gripping of the paper (Figures 1, 3, 9, 12 and 13)

95 It has already been shown that the paper is rolled round the lower ends of the hoppers 48. In order to guard against the rams 42 crushing the sleeves (or tubes) and pushing same out of the cylinders, the tubes are clamped against these hoppers 48 at the top, 100 where they have been rolled round the hoppers 48, by a gripper or pair of tongs, consisting of arms 113 and 114. This device may be omitted if desired.

105 In order to enable the tubes to be folded in at the top, the grippers must release the tubes at a certain instant. This is effected by the arms 113 and 114 being then rotated by projections 118 and 119 respectively on battens 116 and 117 respectively about pivots 115. 110 The closed position, as illustrated, of the grippers is obtained by tension springs 120 being secured between the arms 113 and 114 of adjacent grippers.

115 The moving of the battens 116 and 117 is obtained in the following manner:

On the outer ends of the batten 97 are mounted rods 125 provided with adjusting screws 126.

120 During the ascent of the batten 97 the rods 125 ascend freely through holes 122 in levers 121. During the descent, however, the levers 121 are pressed down against the action of springs 124, whereby the above-mentioned battens 116 and 117 are pushed away by projections 123 in the directions of the arrows, 125 whereby, as above described, the nipping arms 113 and 114 rotate up against the action of the springs 120. When the batten 97 130

ascends again the springs 120 and 124 resume their original condition.

The using of rams of another kind (Fig. 15)

Instead of the ram 42 previously described, a ram 127 may be employed.

The ram 127 centres itself by a cone 129 in a plate 130 and is provided with a strip 128 of fibre or other material. A spring is provided under strip 128.

By means of this spring in the lower position of the ram the fibre is pressed against the paper pushed into the cylinder.

The guiding of the rams 127 in the cone 129 can be adjusted by means of a positioning screw 155.

The exchanging of the fibre of the under part of the ram can be effected by knocking out a key or wedge 156.

20 The mounting of the rams (Figs. 1, 9 and 16)

The ram 42 or 127 must be rotatably secured in the cross bar 52 and must at the same time follow the up-and-down movement of the cross bar. For this purpose the ram is provided with a collar 131 which is pushed into a slot 132 in the cross bar 52, while a centring point 134 secured to a resilient plate 133 holds the ram in its place and enables it to be easily rotated.

In order to enable the bushes 45 and 47 and the indiarubber rings 44 and 46 of the rams 42 to be dismounted, the rams 42 are gripped at their upper ends in a nut member 135 by a screw thread.

Special form of the cylinders (Figs. 7, 9, 11, 17 and 18)

In order to enable the cylinders 158 to be readily exchanged they are preferably made of drawn metal plates and secured against the flat members 157 carried by plates 159.

The constructional example described relates more particularly to the preparation of cigarettes with folded-in ends. It is clear however that the apparatus can also be used for the manufacture of cigarettes without folded-in ends. In this case the movements of the folding devices, or the folding devices themselves, may be omitted.

As mentioned above, all the movements of the individual members are preferably obtained from a single driving shaft, while the individual members themselves are readily exchangeable and their movements adjustable.

What I claim is:—

1. A machine for the simultaneous manufacture of a number of cigarettes comprising a main frame upon which is mounted a number of stationary cylindrical cases in a row, each being made in one piece, in combination with means for introducing a piece of paper into each cylindrical case, means for forming each paper into a tube, means for

closing the lower end of each tube, means for filling the tubes with tobacco, means for tamping the tobacco, means for closing the upper end of the tubes and for forcing the finished cigarettes out of the cases, all the said means being operably connected with and operated from a main driving shaft.

2. A machine for the simultaneous manufacture of a number of cigarettes comprising a number of stationary cylindrical cases arranged in a row, each case being made in one piece and provided with a longitudinal groove or tangential gap, an endless steel band movable periodically and provided with clamps, the mutual distances of which correspond to the length of cigarette paper required for the total number of cylindrical cases, in combination with means for cutting the paper into as many pieces as there are cases and for pushing the cut off pieces through the said grooves or gaps in the cylindrical cases, means for forming each piece of paper into a paper tube, means for closing the lower end of this tube, means for filling said tube with tobacco, means for tamping the tobacco, means for closing the upper end of the paper tube and for forcing the so finished cigarette out of each cylindrical case.

3. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting off the paper into pieces, pushers arranged opposite the cylindrical cases and operating simultaneously to push the cut papers into the respective grooves of the cylindrical cases, in combination with means for forming each piece of paper into a paper tube, means for closing the lower end of this tube, means for filling said tube with tobacco, means for tamping the tobacco, means for closing the upper end of the paper tube and for forcing the so finished cigarette out of each cylindrical case.

4. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting off the paper into pieces, pushers arranged opposite the cylindrical cases and operating simultaneously to push the paper into the respective groove of the cylindrical cases, a ram rotatable in each

- cylindrical case and provided with one or more expansible parts, which press the introduced cigarette paper against the inner wall of the cylinder and carry it round during the rotation of the ram in order to form a paper tube, a mechanism for closing the lower end of the paper tube before the filling thereof with tobacco, distributing rollers, each having a number of grooves on the periphery, the lengths of which are adjustable by means of movable rings with laterally projecting pieces, said rollers discharging the tobacco into filling hoppers ready for tamping into the paper tubes, the hoppers having extension members located in the centre lines of the cylindrical cases and around which the upper ends of the paper tubes are wound, the rotatable ram reciprocating in the cylindrical case to tamp the tobacco, in combination with means for closing the upper end of the paper tube and for forcing the so finished cigarette out of each cylindrical case. 75
5. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting off the paper into pieces, pushers arranged opposite the cylindrical cases and operating simultaneously to push the paper into the respective grooves of the cylindrical cases, a ram rotatable in each cylindrical case and provided with one or more expansible parts, which press the introduced cigarette paper against the inner wall of the cylinder and carry it round during the rotation of the ram in order to form a paper tube, a mechanism for closing the lower end of the paper tube before the filling thereof with tobacco, distributing rollers each having a number of grooves on the periphery the lengths of which are adjustable by means of movable rings with relatively projecting pieces, said rollers discharging the tobacco into hoppers ready for tamping into the paper tubes, the hoppers having extension members located in the centre lines of the cylindrical cases and around which the upper ends of the paper tubes are wound, in combination with means for tamping the tobacco, means for closing the upper end of the paper tube and for forcing the so finished cigarette out of each cylindrical case. 80
6. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting off the paper into pieces, pushers arranged opposite the cylindrical cases and operating simultaneously to push the paper into the respective grooves of the cylindrical cases, a ram rotatable in each cylindrical case and provided with one or more expansible parts, which press the introduced cigarette paper against the inner wall of the cylinder and carry it round during the rotation of the ram in order to form a paper tube, a mechanism for closing the lower end of the paper tube before the filling thereof with tobacco, a single distributing roll having a number of grooves on the periphery, the lengths of which are adjustable by means of movable rings with laterally projecting pieces, said rollers discharging the tobacco into filling hoppers ready for tamping into the paper tubes, the hoppers having extension members located in the centre lines of the cylindrical cases and around which the upper ends of the paper tubes are wound, the rotatable ram reciprocating in the cylindrical case to tamp the tobacco, a mechanism for closing the upper end of the paper tube after the filling thereof with tobacco, in combination with means for forcing the so finished cigarette out of the cylindrical case. 85
7. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting the paper into pieces, pushers arranged opposite each cylindrical case and operating simultaneously to push the paper into the respective grooves of the cylindrical cases, a ram rotatable in each cylindrical case and provided with one or more expansible parts, which press the introduced cigarette paper against the inner wall of the cylinder and carry it round during the rotation of the ram in order to form a paper tube, a mechanism for closing the lower end of the paper tube before the filling thereof with tobacco, a single distributing roll having a number of grooves on the periphery, the lengths of which are adjustable by means of movable rings with laterally projecting pieces, said rollers discharging the tobacco into filling hoppers ready for tamping into the paper tubes, the hoppers having extension members located in the centre lines of the cylindrical cases and around which the upper ends of the paper tubes are wound, the rotatable ram reciprocating in the cylindrical case to tamp the tobacco, a mechanism for closing the upper end of the paper tube after the filling thereof with tobacco, in combination with means for forcing the so finished cigarette out of the cylindrical case. 90
8. A machine for the simultaneous manufacture of a number of cigarettes comprising a number of stationary cylindrical cases arranged in a row, each case being made in one piece and provided with a narrow longitudinal groove or tangential gap, an endless steel band movable periodically and provided with clamps, the mutual distances of which correspond to the length of cigarette paper required for the total number of cylindrical cases, knives for cutting off the paper into pieces, pushers arranged opposite the cylindrical cases and operating simultaneously to push the paper into the respective grooves of the cylindrical cases, a ram rotatable in each cylindrical case and provided with one or more expansible parts, which press the introduced cigarette paper against the inner wall of the cylinder and carry it round during the rotation of the ram in order to form a paper tube, a mechanism for closing the lower end of the paper tube before the filling thereof with tobacco, distributing rollers, each having a number of grooves on the periphery, the lengths of which are adjustable by means of movable rings with laterally projecting pieces, said rollers discharging the tobacco into filling hoppers ready for tamping into the paper tubes, the hoppers having extension members located in the centre lines of the cylindrical cases and around which the upper ends of the paper tubes are wound, the rotatable ram reciprocating in the cylindrical case to tamp the tobacco, a mechanism for closing the upper end of the paper tube after the filling thereof with tobacco, in combination with means for forcing the so finished cigarette out of the cylindrical case. 95

tudinal groove or tangential gap, an endless steel band movable periodically and provided with clamps, the mutual distances of which correspond to the length of cigarette paper
5 required for the total number of cylindrical cases, knives for cutting the paper into pieces, pushers arranged opposite each cylindrical case and operating simultaneously to push the paper into the respective grooves of
10 the cylindrical cases, a ram rotatable in each cylindrical case and provided with one or more expandible parts, which press the introduced cigarette paper against the inner wall of the cylinder and carry it round during the rotation of the ram in order to form a paper tube, a mechanism for closing the lower end of the paper tube before the filling thereof with tobacco, distributing rollers each having a number of grooves on the periphery the lengths of which are adjustable
20 by means of movable rings with laterally projecting pieces, said rollers discharging the tobacco into filling hoppers ready for tamping into the paper tubes, the hoppers having extension members located in the centre lines of the cylindrical cases and around which the upper ends of the paper tubes are wound, the rotatable ram reciprocating in the cylindrical case to tamp the tobacco, this rotatable and reciprocating ram forcing the so finished cigarette out of the cylindrical case.

In testimony whereof I have signed my name to this specification.

35 ISAAC ROET.
